PORTABLE TOOL

Filed Aug. 4, 1930

UNITED STATES PATENT OFFICE

ROBERT E. CROSS, OF CLAREMONT, NEW HAMPSHIRE, ASSIGNOR TO SULLIVAN MACHINERY COMPANY, A CORPORATION OF MASSACHUSETTS

PORTABLE TOOL

Application filed August 4, 1930. Serial No. 472,983.

This invention relates to portable tools, held together by studs 17 and nuts 18, the studs being threaded into the member 15 and passing through openings 19 in the front outer head member 14 so that the cylinder member 11 and the inner heads 12 and 13 are clamped between the portions 14 and 15. A casing member 20 is seated upon shoulders 21 and 22 upon the members 14 and 15 and surrounds the cylinder member 11. This casing is secured, as by small screws 23, to the member 15. The handle 2 is secured to the outer rear head member 15 by screws 25.

One object of the invention is to provide an improved portable tool. Another object of the invention is to provide an improved pressure fluid operated motor. A further object of the invention is to provide an improved pressure fluid motor having improved governing means. A still further object of the invention is to provide an improved governing means for pressure fluid motors. Other objects and advantages of the invention will subsequently appear.

In the accompanying drawing in which for purposes of illustration two forms of the invention are shown,

Fig. 1 is a central longitudinal section through an illustrative embodiment of the invention.

Fig. 2 is a fragmentary sectional view through the motor, the view being taken on planes corresponding to the line 2-2 of Fig. 3.

Fig. 3 is a section on the line 3-3 of Fig. 2.

Fig. 4 is a longitudinal fragmentary sectional view on the line 4-4 of Fig. 5 showing a modified form of construction.

Fig. 5 is a transverse section through the modified arrangement.

Referring to the drawing, and particularly to Figs. 1 to 3 thereof, 1 indicates a pressure fluid operated portable tool of the grinder type in which the illustrative embodiment of my invention is incorporated. This portable tool 1 comprises a rear handle section 2, a motor section 3, and a front handle portion 4. A suitable tool, herein a grinding wheel 5, is suitably mounted upon a spindle 6 which is supported in a series of bearings 7, 8 and 9. The bearing 7 is arranged in the forward end of the handle 4, the bearing 8 to the rear of the handle 4, and the bearing 9 forwardly of the handle 2. The motor 3 comprises a cylinder block 11, a pair of inner heads 12 and 13, a forward outer head 14 formed integral with the handle 4, and a rear outer head and governor housing 15. The parts of the motor so far described are rigidly

Referring to Figs. 2 and 3 it will be noted that the cylinder member 11 is cylindrically bored as at 27 and that the axis of the spindle 6 is offset from the axis of the cylindrical bore 27. The space between the inner head members 12 and 13 is divided into two compartments by an intermediate head member 28 which is held in central position by the set screws 29. The space surrounding the exterior of the cylinder member 11 and the sleeve member 20 serves as an exhaust space, as hereinafter described, and it will be noted that the sleeve member 20 is arranged coaxially with the spindle 6. The spindle 6 is bored centrally at its rear end, as indicated at 31, and near the forward end of the bore 31 a radially extending passage 32 opens into an annular groove 33 within the partition member 28. A radial passage 34 extends to the periphery of the partition 28 and has laterally opening ports 35 which open into chambers 36 and 37 respectively located at opposite sides of the partition member 28. The ports 35, which are inlet ports, open into the chambers 36 and 37, which constitute cylinders proper, a short distance, in the direction of rotation, ahead of the point in the wall of the bore 27 which is nearest to the axis of the spindle 6.

The spindle 6 carries suitably keyed thereto and one within each of the chambers 36 and 37, cylindrical rotor elements 39 and 40, these rotor elements being coaxial with the spindle and of a diameter such that their peripheries substantially contact with the inner wall of the bore 27 at the point in the latter nearest the axis of the spindle 6. Each of the rotor members 39 and 40 is provided

with a pair of radial slots 41. The slots in each rotor are arranged in a common diametric plane so that they open oppositely to each other through the periphery of the rotor. The slots in the two rotors are at right angles to each other. Within the slots 41 there are slidably mounted radially movable vanes 42, preferably of micarta, bakelite, or other suitable similar material, though it will be obvious that metallic vanes may be used if desired. At the opposite side of the line of substantial contact between the rotors and the bore of the cylinder member a series of exhaust ports 43 open radially outward and connect the cylinder bores with the space between the members 11 and 20. This space therefore serves as an exhaust chamber and through its connection through a series of fine holes 44 with the atmosphere, permits a nearly silent escape of the exhaust fluid.

A regulated supply of motive fluid is supplied to the motor under both manual and automatic control. The handle 2 contains a throttle valve 46 provided with an operating lever 47. This throttle valve controls the flow of motive fluid from an inlet supply connection 48 through a passage 49, past the throttle valve 46, through the space within the valve seat 50, and then through a passage 51 into a chamber 52 formed within the member 15. The throttle valve is normally maintained closed by a spring 53. Lubricant may be supplied to the incoming air from a chamber 54 within the handle 2 through a passage 55.

Within the chamber 52 there is mounted a governor mechanism which comprises a hollow spindle 57 supported in the rear end of the drive spindle 6 and rotated by the latter through a pin and slot connection 58. The hollow spindle 57 is closed at its rear end but its internal passage 59 communicates through radially opening ports 60 with the interior of the chamber 52. The sliding sleeve 61 normally held in abutment with a shoulder 62 herein formed integral with the spindle 57 is movable to close and open the ports 60 and thereby control the entrance of motive fluid into the bore 59 and its resultant passage to the motor. The shoulder 62 is provided at diametrically opposite points with pairs of ears 64 between which pivot pins 65 support pivoted weights 66 whose heavier ends 67 tend to move out as the speed of the motor increases, thereby causing their shorter rear ends 68 to move the sleeve 61 against the pressure of a spring 69 to close communication through the port 60 between the chamber 52 and the bore 59. The spring tension may be adjusted by adjustably positioning a follower 70 which may be held in a plurality of positions by means of a cotter pin 71 insertible in a series of holes 72.

From the description thus far given, the mode of operation of this embodiment of the

invention will be clearly apparent. The operator will grasp the tool by the handle 2 and by the handle portion 4, and by gripping the operating lever 47 of the throttle valve, will open the throttle valve 46 and permit the air to flow from the supply connection 48 through passage 49 and passage 51 into the chamber 52 from which it will next pass through ports 60, bore 59, bore 31, radial passage 32, groove 33, and radial passage 34 to the laterally opening inlet ports 35, thus entering the cylinders proper 36, 37. Here the fluid will act upon the vanes 42, causing rotation of the rotors 39 and 40 and therefore of the spindle 6. When the vanes overrun the exhaust ports 43, exhaust takes place into the outer chamber in the sleeve 20 and the exhaust fluid finally escapes to the atmosphere through the ports 44.

It will be evident that as the motor speeds up and approaches the desired maximum speed, the heavier ends 67 of the governor weights 66 will swing outward with the result that the governor sleeve 61 will be moved gradually to close the ports 60, thereby preventing over-speeding of the motor.

From the foregoing description it will be clear that there is provided in the mechanism described, a pressure fluid operated motor having very simple fluid supply connections, one of adequate starting torque and very uniform running torque, that the air is economically used, and that a minimum number of machine operations are necessary in the production of the motor. It will also be clear that the governor is readily accessible by the removal of the rear handle 2 and the withdrawal of the governor spindle 57 from its connection with the spindle 6 of the motor. By reason of the arrangement of the fluid supply passages altogether in the spindles and in the partition plate 28, the construction of the cylinder of the motor is made exceedingly simple and inexpensive.

In Figs. 4 and 5 a modified form of construction is illustrated. This type of construction differs from that shown in Figs. 1 to 3 only in the modified arrangement of passages and ports for the admission of motive fluid to the cylinder chambers 36 and 37. In this form, instead of admitting the motive fluid laterally to the chambers 36 and 37 through inlet ports 35, provision is made for the admission of the fluid inwardly at spaced points along the periphery of the cylinder. It will be noted that the cylinder member 11' is provided with a longitudinally extending enlargement 75 which is traversed by a longitudinally extending passage 76 running from end to end of the cylinder block. This passage is connected through an opening 77 at its central portion with a radially extending passage 34' in the intermediate partition member 28' and a series of ports 78 open inwardly through the wall of the cylinder mem-

ber 11' at suitably spaced intervals to admit fluid to the chambers 36' and 37'.

The mode of operation of this arrangement is substantially identical with that of the other species. It may be noted that in this case the fluid flows through the bore 31, annular groove 33, radial passage 34', port 77, longitudinally extending passage 76, and inwardly opening ports 78 to operate the rotors in precisely the same manner, generally speaking, as in the first described embodiment of the invention.

This form of the invention also is obviously inexpensive to manufacture and possesses substantially all of the operating advantages of the embodiment first described.

While there are in this application specifically described two forms which the invention may assume in practice, it will be understood that these forms of the same are shown for purposes of illustration and that the invention may be modified and embodied in various other forms without departing from its spirit or the scope of the appended claims.

25 What I claim as new and desire to secure by Letters Patent is:

1. In a rotary pressure fluid operated motor, a cylinder member, heads therefor, a partition within said cylinder member dividing the interior of the latter into different rotor chambers, rotors in said chambers, a spindle supporting said rotors, and fluid distribution means for said rotor chambers including a fluid supply passage extending through said spindle and said partition.

2. In a rotary pressure fluid operated motor, a cylinder member, heads therefor, a partition within said cylinder member dividing the interior of the latter into different rotor chambers, rotors in said chambers, a spindle supporting said rotors, fluid distribution means for said rotor chambers including a fluid supply passage extending through said spindle and said partition, and ports opening laterally through the walls of said partition adjacent the periphery thereof.

3. In a rotary pressure fluid operated motor, a cylinder member, heads therefor, a partition within said cylinder member dividing the interior of the latter into different rotor chambers, rotors in said chambers, a spindle supporting said rotors, and fluid distribution means for said rotor chambers including a fluid supply passage extending through said spindle and said partition, and a longitudinally extending passage formed in said cylinder member and having ports opening inwardly into said rotor chambers.

4. In a rotary pressure fluid operated motor, a cylinder member, and members cooperating with said cylinder member to form a rotor chamber, one of said members having a radially extending passage formed therein and a lateral port opening into the bore of the rotor chamber, a rotor in said chamber, a

supporting shaft therefor, fluid supply connections including a passage in said shaft communicating with said radially extending passage, and means for exhausting fluid from said rotor chamber.

5. In a rotary pressure fluid operated motor, a cylinder member, members cooperating therewith to form a rotor chamber, a rotor in said chamber, a shaft upon which said rotor is mounted, said rotor shaft being hollow, passage means formed in the wall of said rotor chamber connecting the interior of said hollow shaft with said rotor chamber for admitting fluid to the latter, exhaust means for said rotor chamber, and means for admitting a governed supply of motive fluid to said hollow shaft including a governor supported coaxially with the latter and controlling the admission of fluid thereto.

6. In a rotary pressure fluid operated motor, a cylinder member, members cooperating therewith to form a rotor chamber, a rotor in said chamber, a shaft upon which said rotor is mounted, said rotor shaft being hollow, passage means formed in the wall of said rotor chamber connecting the interior of said hollow shaft with said rotor chamber for admitting fluid to the latter, exhaust means for said rotor chamber, and means for admitting a governed supply of motive fluid to said hollow shaft including a governor supported coaxially with the latter and controlling the admission of fluid thereto, said governor including a hollow spindle rotating with said shaft and having an internal chamber communicating with the bore of said shaft and ports opening from the periphery of said spindle into said internal chamber and speed controlled means controlling said ports.

7. In a rotary pressure fluid operated motor, a cylinder member, and members cooperating with said cylinder member to form a rotor chamber, a rotor in said chamber, a supporting shaft therefor, fluid supply connections including a passage in said shaft and a communicating, radially extending passage in one of said members which cooperate with the cylinder member to form a rotor chamber, and means for exhausting fluid from said rotor chamber.

In testimony whereof I affix my signature.

ROBERT E. CROSS.
